UNITED STATES PATENT OFFICE.

JOSEPH OSCAR GRENIER, OF VANCOUVER, BRITISH COLUMBIA, CANADA.

ROPE PULLER.

Application filed September 15, 1927. Serial No. 219,769.

My invention relates to improvements in rope pulling devices which are particularly adapted for use by linemen and others in stretching cables, tightening guy wires on towers and the like. The objects of the invention are to provide means applicable particularly to the rope puller patent granted to me in the United States, February 16th, 1926, under Number 1,573,397, whereby the rotation of the screw rack is effected by a simple lever having a ratchet mechanism capable of being quickly adjusted for operation in either direction. A further object is to provide a split nut mechanism adapted to engage the screw rack and be quickly released therefrom to facilitate the resetting of the puller for taking another pull on the rope, which nut is so designed as to be immune from jamming due to the presence of mud or ice 20 and snow or such other conditions as are encountered by linemen in their work.

The invention consists essentially of a pul- 25 ler having a screw rack to the end of which a rope is adapted to be attached and which is rotated in opposite directions by a ratchet lever having a lever capable of reversing the direction of drive imparted by the ratchet lever, and a split nut engaging the screw, which nut is provided with a parallel move- 30 ment and is actuated by a turn button to release it from or reinstate engagement with the screw, as will be more fully shown in the accompanying drawings and described in the following specification, in which:—

Fig. 1 is a general view of the invention.

Fig. 2 is an enlarged view of the ratchet mechanism with the cover plate broken away.

Fig. 3 is a plan view of the split nut mechanism.

Fig. 4 is a front view showing the nut open with the cover plate removed.

Fig. 5 is a front view showing the nut closed about the screw rack with the cover plate removed.

Fig. 6 is an end view of the split nut mechanism.

In the drawings like characters of reference indicate corresponding parts in each figure.

The numeral 1 indicates generally a frame comprising a pair of parallel guides 2 which are connected together at their lower ends with a transverse member 3 having a swivel mounted hook 4 and at the upper ends with a transverse member 5 which is centrally ap- 55 tured as at 6 and is provided with a hexagonal recess 7, the purpose of which will herein-

after appear. Slidably movable through the aperture 6 and the recess 7 is a screw rack 8 which is fitted at its upper end with a swivel hook 9 and is journalled at its lower end in an endwise movable crosshead 10 which is 60 slideable upon the guides 2. The screw rack is fitted adjacent the crosshead 10 with a bevelled pinion 11 which is engaged by a bevelled gear 12 keyed to a shaft 13 suitably 65 journalled upon a bracket 14 which is formed integrally with the crosshead 10. Rotatably mounted upon the outer end of the shaft 13 is a ratchet lever generally indicated by the numeral 15 which is adapted to engage a ratchet 70 wheel 16, see Figure 2, which is secured to the shaft 13. The ratchet lever 15 terminates at its inner end in a jaw 17 having front and rear plates 18 which are apertured to fit the shaft 13 and are spaced apart to accommodate the 75 ratchet pinion. Extending between the plates 18 are pins 19 upon which a pair of opposed pawls 20 are adapted to alternately engage the wheel 16 and are each provided with an in- 80 wardly directed tongue 21. This tongue is 85 adapted to be engaged on its inner side by a cam 22 which is mounted on a pin 23 and is provided with a lever 24 by which it is moved to engage either of the pawls 20. A C spring 25 is carried within the jaw 17, the outer ends 90 of which are adapted to exert an inward pres- 95 sure upon each of the pawls 20, so that the pawl which is not held outwardly by the cam 22 may be free to engage the ratchet wheel 16.

Freely mounted upon the screw rack 8 is a collar 26 having opposing hook members 27 which are adapted to embrace the guide rods 2. Pivottally mounted upon the face of the collar is a turnbutton 28 having a pro- 95 jecting lever 29 by which it is turned.

The numeral 30 indicates a nut divided along its longitudinal axis into halves 31 and 32, which halves are fitted with overhanging rack members respectively indicated by the numerals 33 and 34 and are each provided 100 with a vertical slot 35 with which the ends of the turn button 28 mesh. The rack member 33 is provided with a horizontal slot 36, and the rack member 34 is provided with a corresponding tongue 37 both of which co- 105 operate to provide a parallel movement be- 110 tween the two as the lever 29 is turned to ac- tuate the turnbutton 28, so that the halves 31 and 32 of the nut 30 are moved in parallel re- lation to each other to release, or mesh with the thread of the screw rack 8.

The numeral 38 indicates a cover plate se-

cured to the collar 26 in any suitable manner and preferably provided with lower and upper inturned flanges 39 and 40 respectively, the former bearing on the collar and the latter engaging the edge of the rack members 33 and 34 and forming a guide therefore along which the rack members have movement as the lever 29 is operated to open or close the nut.

10 In operating the puller the hook 4 is attached by a rope to a suitable anchorage and the rope to be pulled is attached to the hook 9. The lever 24 is set as required for adjusting the pawls 20 to engage the ratchet wheel 15 in the proper direction, when the operation of the ratchet lever 15 will impart rotation and endwise movement to the screw rack 8, thus exerting a pull on the rope (not shown). When it is desired to take a further pull 15 upon the rope, it is secured by any suitable device and the puller disconnected therefrom, endwise movement is imparted to the screw rack 8 causing the half nuts 31 and 32 to be withdrawn from the socket 7. It then suffices to open the nut by moving the lever 29 and to slide the screw rack 8 outwards through the collar 26 and the upper transverse member to any desired distance, then to close the nut and reinsert it in the recess 20 7, when the puller is ready for reuse.

What I claim as my invention is:

1. In a rope puller comprising a pair of slides connected by transverse members, one of said members having a recess, a screw rack 35 adapted for attachment to the rope to be pulled and having endwise movement through said recess, a split nut engaging said screw rack and normally housed in said recess, said nut comprising a pair of half portions 40 slidably connected to a collar slidably movable along the screw rack, and means for imparting parallel movement to the half portions.

2. In a rope puller comprising a pair of

slides connected by transverse members, one of said members having a recess, a screw rack 45 adapted for attachment to the rope to be pulled and having endwise movement through said recess, a non-rotative collar having endwise movement upon the screw rack, a split nut consisting of two divided half portions slidably connected to said collar, a turn button having a lever pivotally mounted upon the collar and engaging the half portions whereby as the lever is turned 50 opposite parallel movement is imparted to the half portions of the split nut.

3. In a rope puller comprising a pair of slides connected by transverse members, one of said members having a recess, a screw rack 60 adapted for attachment to the rope to be pulled and having endwise movement through said recess, a non-rotative collar having endwise movement upon the screw rack, a split nut consisting of two divided half 65 portions, having rack members slidably connected together and to said collar, and means for imparting opening and closing movement to the half nut portions.

4. In a rope puller comprising a pair of 70 slides connected by transverse members, one of said members having a recess, a screw rack adapted for attachment to the rope to be pulled and having endwise movement through said recess, a non-rotative collar 75 having endwise movement upon the screw rack, a split nut consisting of two divided half portions having rack members one of which is provided with a horizontal parallel sided slot and the other having a tongue slidably movable therein, means connecting the members to the collar, and means for imparting opening and closing movement to the half nut portions.

Dated at Vancouver, B. C. this 27th day of 85 August, 1927.

JOSEPH OSCAR GRENIER.
